[57]

ABSTRACT

A key holder comprising a key ring formed from a length of resilient wire stock and bent to provide a loop and a pair of leg portions, a discoidal body formed of plastic, means for mounting a flat, indicia-bearing element on at least one side of said body, said key ring leg portions being detachably engageable within said body inwardly of the indicia-bearing element, and panel-like components for retaining said leg portions against accidental displacement, protecting the indicia-bearing elements against damage thereby.

2 Claims, 7 Drawing Figures

KEY HOLDER

BACKGROUND AND SUMMARY OF THE INVENTION

This invention relates in general to portable article retaining devices and, more particularly, to a key holder constituted of a ring-forming member and a body detachably engageable with the former.

It is an object of the present invention to provide a key holder incorporating a key ring formed from a length of resilient wire stock and a body detachably engageable with said key ring, and wherein the ends of said ring are received internally within the body, thereby being obscured from view during usage as distinguished from key holders of the general type wherein the leg portions are engaged on external portions of the related body and, hence, fully visible.

Another object of the present invention is to provide a key holder of the type stated wherein the body is adapted to receive flat, indicia-bearing elements, and having panel components for preventing the received key ring legs from disruptive, damaging contact with said indicia-bearing elements during usage.

It is another object of the present invention to provide a key holder of the type stated wherein the body integrally incorporates novel structural members for retention of the key ring legs.

It is a further object of the present invention to provide a key holder of the type stated which is adapted to securely maintain keys thereon and wherein the engagement between said key ring and the body conduce to a reliably stable interengagement thereby preventing unauthorized accidental displacement of the keys thereon.

It is a still further object of the present invention to provide a key holder of the type stated which is particularly designed for inexpensive manufacture of the components and ease of assembly thereof.

It is another object of the present invention to provide a key holder of the type stated which is durable and reliable in usage, which is particularly adapted to prevent loss of the indicia-bearing elements so that the said holders are suited for advertising and promotional purposes; and which is of light weight so as to avoid imposing an unduly heavy bulk within the user's pockets; and which is adapted for high volume, rapid production.

BRIEF DESCRIPTION OF THE DRAWINGS

FIG. 1 is a front plan view of a key holder constructed in accordance with and embodying the present invention.

FIG. 2 is a side view.

FIG. 3 is a horizontal view taken on the line 3—3 of FIG. 1.

FIG. 4 is a horizontal transverse sectional view taken on the line 4—4 of FIG. 1.

FIG. 5 is a vertical transverse sectional view taken on the line 5—5 of FIG. 1.

FIG. 6 is a vertical transverse sectional view taken on the line 6—6 of FIG. 2.

FIG. 7 is a vertical transverse sectional view taken on the line 7—7 of FIG. 2.

DESCRIPTION OF THE PREFERRED EMBODIMENT

Referring now by reference characters to the draw-

ings which illustrate the preferred embodiment of the present invention, A generally designates a key holder comprising a key ring 1 and a unitary retainer or discoidal body 2. Said key ring 1 is formed from a length of resilient wire stock bent to define a loop or partannular section 3 for receiving keys (not shown) and a pair of legs 4,4' each of which at their end extremity or outer terminal, as at 5,5', respectively, is directed slightly toward the other. At their opposite ends, immediately adjacent loop 3, legs 4,4' are bent inwardly toward each other, as at 6,6', to form a relatively narrow neck n. Between their outer terminals 5,5', and neck portion 6,6', each leg 4,4' is curved or arcuated outwardly away from each other, as at 7,7', respectively. For purposes presently appearing, the resilient nature of the material of construction of key ring 1 will allow legs 4,4' to be urged toward and away from each other but with the development of expected stress.

Retainer 2 is formed, preferably, by molding from 20 butyrates, which plastics have been found to have the desired strength and lightness of weight particularly suitable for the present invention. Said retainer 2, as stated, is of general discoidal configuration embodying a rim portion r comprising an outer or peripheral side wall 8 having its end faces beveled, as at 9,9', for border-defining purposes, as will be set forth hereinbelow. The inner surfaces of said beveled margins 9,9' are provided with a continuous undercut 10,10', respectively; with there being an inner side wall 11, of slightly greater depth than said outer side wall 8, being presented between undercuts 10,10' (see FIG. 4). Extending between diametrically opposed portions of inner side wall 11, and of like thickness and planarwise aligned therewith, is a partition or post 12. It will be seen that partition 12 divides the interior of retainer 2 into two distinct sections. Integral with one end face of partition 12, is a relatively thin, continuous wall 13 planarwise parallel to the axis of partition 12 and merging along its periphery with the adjacent portion of inner side wall 11. As may be seen in FIG. 4, said wall 13 is of relatively reduced thickness with respect to the depth of inner wall 11 and partition 12. Wall 13 provides a surface against which may be disposed a flat, annular indicia-bearing member 14, as formed of paper or the like, and carrying upon its outwardly directed face a design and/or textual matter, as for advertising, promotional, or other intelligence purposes. Said members 14 project in their peripheral portions into the undercut 10', and coveringly disposed over said member 14 is a protective transparent window or lens 15, as fabricated of clear plastic, with its margins received within the undercut 10' and thereby held firmly against accidental displacement.

Partition 12 in its end portion opposite from that connected to wall 13 is rigid with a relatively small flat plate 16 which is planarwise parallel with wall 13 and projects laterally beyond each side of partition 12 a limited distance but spacedly from the proximate portions of inner side wall 11; the normally upper end of said plate merges into said wall 11, as at 17, immediately adjacent apertures 18, 18' provided in rim portion r for opening into the interior of retainer 2, on opposite sides of partition 12. The normally lower end of plate 16, as at 19, is spaced from the bottom portion of rim portion r but is connected thereto in its opposite lower side portions by narrow arms 20,20' which bridge the distance between said plate and said rim portion r for

rigidifying the said plate 16 as well as to enhance the effective surface provided by same for receiving thereon a member 14 which is similarly accepted in its periphery within undercut 10. Just as with the opposite side of key holder A, a protective transparent window or lens 15 is disposed converingly over the member 14 supported on plate 16 and with the edge portions of said window extending beneath undercut 10.

Key ring 1 is adapted for detachable engagement with retainer 2, with such being effected by projection of legs 4,4' through apertures 18,18', respectively, for extension into the interior of retainer 2 on opposite sides of partition 12 and between wall 13 and plate 16. The walls of aperture 18,18' effect a camming relationship with the respective legs 4,4' so that as the arcuated portions 7,7' pass therethrough said legs will be forced toward each other with the development of expected stress. After completion of passage through said apertures 18,18' by the arcuated portions 7,7', the latter under inherent bias will return to normal relationship, thereby extending slightly laterally outwardly of apertures 18,18' in which position accidental dislodgment is inhibited.

In order to withdraw key ring 1 from retainer 2, forceful, axially directed outward pulling is required to cause legs 4,4' to be cammed toward each other against the bias of the wire stock for sufficient mutual compression.

It is to be particularly noted that wall 13 and plate 16 serve to confine the legs 4,4' of key ring 1 when the same are engaged within retainer 2. It is recognized that during usage there may be some rocking or shifting of such legs which would normally have a damaging and disruptive effect upon the members 14, causing a tearing or other rupturing thereof which would effectively destroy the value of the message or other symbol provided thereon. Thus, regardless of how loose key ring 1 might become the legs thereof cannot be brought into damaging contact with members 14 so that the longevity of key holder A is assured. Furthermore, wall 13 and plate 16 both serve to provide the proper supports for members 14 so that the same are at all times retained in appropriately centered, unwrinkled condition.

Having described my invention what I claim and desire to obtain by Letters Patent is:

1. A key holder comprising a key ring formed from wire stock and having a loop-forming portion and a pair of spaced-apart legs continuous with said portion, a discoidal retainer body having a rim comprising an outer peripheral wall, an inwardly radially spaced inner peripheral wall and opposed exterior surfaces between said inner and outer peripheral walls, said rim having a pair of openings extending therethrough from said

outer peripheral wall through said inner peripheral wall, an elongated partition member provided internally of said retainer body with opposite sides thereof aligned respectively with the said openings, said inner peripheral wall being annular, said partition member extending between diametrically opposed points on said inner peripheral wall, said key ring legs projecting through said openings and being presented on opposite sides of said partition member, an annular, flat, uniplanar, relatively rigid plate integral with one side of said partition member with its plane being parallel to the major axis of said partition member, said inner peripheral wall being provided with undercut portions, said plate being integral at its periphery with the said inner peripheral wall, and being located inwardly of the undercut portion proximate thereto, a first indicia-bearing member presented flatwise upon said annular plate, and a first protective transparent member disposed coveringly of said first indicia-bearing member, said first indicia-bearing member and said first protective transparent member having peripheral portions received within the proximate undercut portion of said inner peripheral wall, a second plate presented in planar parallel relationship to said annular plate and being disposed integral to the opposite side of said partition member, said second plate having an area less than that of said annular plate with portions of its periphery spaced from said inner peripheral wall, said second plate being integral with said inner peripheral wall at spaced apart points between the said portions of its periphery spaced from said inner peripheral wall, and further characterized by said co-ordinating plate projecting beyond opposite lateral portions of said partition member a distance sufficient to partially overlie the received key ring legs whereby the latter are retained between said first and second plates, further characterized by the engaged portions of the second plate to said inner peripheral wall constituting a portion thereof proximate the pair of rim openings and arms extending from said second plate to the inner peripheral wall at spaced-apart points from each other and from the portion engaging said wall proximate the pair of rim openings.

2. A key holder as defined in claim 1 and further characterized by a second indicia-bearing member disposed upon said second plate and having its marginal portions received within the adjacent undercut of said inner peripheral wall, and a second transparent protective member disposed coveringly of said second indicia-bearing member with the marginal portions of said second protective member being accepted within such undercut.
